[57] CLAIM

The ornamental design for a combination book rack and tissue dispenser, substantially as shown.

DESCRIPTION

FIG. 1 is a reduced front perspective view of a combination book rack and tissue dispenser showing my new design.

FIG. 2 is a front elevational view thereof.

FIG. 3 is a top plan view thereof.

FIG. 4 is a bottom plan view thereof.

FIG. 5 is a left side elevational view thereof.

FIG. 6 is a central vertical sectional view thereof.

FIG. 7 is a rear elevational view thereof.

FIG. 8 is a reduced front perspective view of a second embodiment of the combination book rack and tissue dispenser, it being understood that the undisclosed bottom, side and rear are the same as in FIGS. 4, 5 and 7 respectively.

FIG.8

FIG.1

FIG.3
